US0D1111072S

(12) **United States Design Patent** (10) **Patent No.:** **US D1,111,072 S**
(45) **Date of Patent:** **** Feb. 3, 2026**

(54) **TRANSFER ROBOT**

(71) Applicant: **SHENZHEN PUDU TECHNOLOGY CO., LTD.**, Guangdong (CN)

(72) Inventors: **Peng Chen**, Guangdong (CN); **Xiaolin Zhu**, Guangdong (CN)

(73) Assignee: **SHENZHEN PUDU TECHNOLOGY CO., LTD.**, Shenzhen (CN)

(**) Term: **15 Years**

(21) Appl. No.: **29/971,800**

(22) Filed: **Nov. 6, 2024**

(30) **Foreign Application Priority Data**

(57) **CLAIM**

The ornamental design for a transfer robot as shown and described.

DESCRIPTION

FIG. 1 is a front and right side perspective view of a transfer robot showing our new design;

FIG. 2 is a rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the transfer robot which form no part of the claimed design.

1 Claim, 8 Drawing Sheets
